UNITED STATES PATENT OFFICE.

MARTIN P. SMITH, OF ST. LOUIS, MISSOURI, ASSIGNOR TO WELCOME F. SWEET, OF ST. LOUIS, MISSOURI.

STREET-CAR ADVERTISING APPARATUS.

1,080,728.

Specification of Letters Patent.

Patented Dec. 9, 1913.

Application filed April 10, 1913. Serial No. 760,250.

To all whom it may concern:

Be it known that I, MARTIN P. SMITH, a citizen of the United States, residing at St. Louis, Missouri, have invented a certain 5 new and useful Improvement in Street-Car Advertising Apparatus, of which the following is a full, clear, and exact description, such as will enable others skilled in the art to which it appertains to make and use the 10 same, reference being had to the accompanying drawings, forming part of this specification, in which—

Figure 1 is a sectional view through the upper portion of a car which is equipped 15 with an advertising apparatus of my improved construction. Fig. 2 is a diagrammatic view illustrating the arrangement of the card-carrying frames within the housing. Fig. 3 is an enlarged vertical section 20 taken approximately on the line 3—3 of Fig. 1. Fig. 4 is an elevational view with parts in section and parts broken away of the means employed for returning the card-carrying frames from one end of the car to 25 the other after said frames have passed through the advertising apparatus and been displayed through the openings therein, said view being taken approximately on the line 4—4 of Fig. 3. Fig. 5 is a horizontal 30 section taken approximately on the line 5—5 of Fig. 3. Fig. 6 is a fragmentary section taken approximately on the line 6—6 of Fig. 5. Fig. 7 is a detail section taken approximately on the line 7—7 of Fig. 4. Fig. 8 35 is a sectional view of the valve which controls the inlet and outlet of air to and from the fluid-pressure-actuated means which is utilized for effecting a return movement of the cards through the apparatus.

40 My invention relates generally to advertising apparatus, and more particularly to an advertising apparatus especially designed and adapted for use in street cars and like passenger transporting vehicles, al- 45 though the apparatus herein shown and described can, with slight structural changes, be advantageously used for displaying advertising cards in railway stations, waiting rooms, hotel lobbies and show windows.

50 The principal objects of my invention are: first, to provide a simple, inexpensive and easily operated advertising apparatus wherein in a housing or container is provided with a series of openings, spaced apart, and to ar-

range for movement in said housing a series of independent, unattached card-carrying frames or members which are displayed through said openings; second, to provide means whereby the display members or frames are arranged in series behind each opening in the housing, and to shift the front members of each series to the rear of the next succeeding series, thereby doing away with the continuous display or panoramic effect such as is ordinarily obtained in devices of this character; third, to provide simple means for returning the display members to the starting point after said members have been moved through the apparatus, and displayed through the openings therein, which means also effects a movement of the front display member of each series to a position in the rear of the next adjacent series,—and fourth, to provide a comparatively simple structure arranged and constructed so as to take up comparatively little space within the car.

To the above purposes my invention consists in certain novel features of construction and arrangement of parts hereinafter more fully described and claimed.

In the drawings I have illustrated my improved apparatus applied to a street car, and where such application is made, the apparatus is positioned in the space immediately above the windows in the side of the car.

Referring by numerals to the accompanying drawings, 10 designates the side plate of the car and 11 the roof sheet which extends from said side plate up to the deck plate. Fixed to the side wall of the car immediately above the windows and in front of the side plate 10 is a molding strip 12, and fixed to the upper edge thereof and spaced apart from the side plate 10 is a second molding strip 13. Fixed to the roof structure of the car immediately below the deck plate is a molding strip 14, from the lower edge of which projects inwardly and downwardly a narrow ledge or strip 15.

It will be understood that the molding strips 12, 13, 14 and 15 extend from one end of the car to the other, thereby forming a compartment of sufficient size to contain the operating parts of my improved advertising apparatus.

Arranged between the strips 13 and 15

are fixed panels 16, the same being suitably spaced apart to form openings 17, through which the advertising cards are displayed, and in practice I prefer to make these panels 16 with a width equal to approximately half the length of one of the openings 17. These panels can be ornamented as desired to conform with the interior decorations of the car.

Arranged between the upper portions of the side plate 10 and molding strip 13 is a horizontally disposed plate 18, and fixed to the central portion of said plate and extending upward to the molding strip 14 and parallel with the roof sheet 11 is a partition 19. The space between this partition and the panels 16 is occupied by the various sets of card-carrying frames which are, in turn, displayed through the openings 17, and the space between said partition and the roof sheet 11 is occupied by the cards which are being returned to the starting end of the apparatus. The ends of this partition 19 do not extend all the way to the ends of the car, sufficient space being left between the ends of the partition and the car ends for the movement of the cards from one compartment to the other.

Arranged a short distance below the plate 18 and fixed to the upper end of the molding strip 12 is a horizontally disposed plate 20, the outer edge of which terminates a short distance from the side plate 10. Journaled in suitable bearings on this plate and on the side plate 10 is a series of grooved rollers 21 arranged at suitable distances apart, and the upper portions of these rollers project through the space between the plates 10 and 20. Supported upon these grooved rollers 21 is a metal rail or bar 22 which extends practically the entire length of the apparatus, and pivotally mounted on the upper edges of said bar and arranged at suitable distances apart are dogs or pawls 23, the free ends of which are normally elevated by springs such as 24, which latter are fixed to the bar 22. These dogs or pawls move longitudinally with the bar 22 as the same is reciprocated, and the forward upper ends of said dogs project upwardly through a slot 25 which is formed in the outer portion of the plate 18. These dogs are for the purpose of engaging the lower corners of the card-carrying frames at one end to move said frames through the compartment between the partition 19 and roof sheet 11. Connected to one end of this bar 22 is a flexible member 26 which passes over a suitably mounted pulley 27, and connected to said flexible member is a weight 28.

Positioned within the housing immediately below the end of the bar 22 to which the flexible member 26 is connected, and supported in any suitable manner is a cylinder 29 in which is arranged for operation a piston 30 having a piston rod 31 which is

connected by means of a bracket 32 to the bar 22. The cylinder 29 is of such length that the piston operating therein has a stroke approximately equal to the length of one of the card-carrying frames plus the length of one of the panels 16. Positioned on the outer end of the cylinder 29 is a valve housing 33 having a nipple 34, to which is detachably connected one end of a fluid-pressure supply pipe 35. Formed in the housing 33 is an axially arranged chamber 36, and intersecting the same and leading from the nipple 34 to the interior of the cylinder 29 is a port 37. Arranged for sliding movement in the chamber 36 is a tubular valve 38 provided on its inner end with a plug 39 having a head 40 which operates in the inner end of the chamber 36. This head is spaced a short distance from the inner end of the tubular valve 38. Formed in the inner end of the tubular valve 38 is a single aperture 41, which, when the valve has been moved inward to its limit of movement, registers with that portion of the port 37 which is between the chamber 36 and the chamber within the cylinder 29. Formed through the outer portion of the tubular valve 38 is a series of apertures 42. Fixed in the outer end of the tubular valve 38 is a short rod 43 which operates through a suitably fixed bearing 44, and mounted on the outer end of said tubular valve is a finger 45 which is adapted to be engaged by brackets 46 and 47, which latter are carried by the bar 22. The bracket 46 engages the finger 45 and moves the valve 38 inward when the bar 22 is moved in one direction under the influence of the piston 30, and the bracket 46 engages said finger to move the valve outward as the bar 22 is shifted by means of the weight 28. A port 48 is formed through the housing 33 at the inner end of the chamber 36 and permits air to enter and escape from the inner end of said chamber as the head 40 moves backward and forward therein.

Formed in the plate 18 near the front edge thereof and immediately to the rear of each opening 17 is a longitudinally extending slot 49, and one end of said slot is extended in an oblique direction toward the partition 19, as designated by 49a, said oblique portion of the slot occupying a position behind the corresponding panel 16. Located immediately behind the panel and the oblique portion of each slot is a wedge-shaped block 50 which is for the purpose of guiding the forward ends of the card-carrying frames as they are shifted from one series to the next adjacent series.

Located on the plate 18 near the point where the oblique portion 49a of the slot joins the straight portion 49, is a transversely disposed block 51 which is for the purpose of maintaining the rear card-carrying frames in proper position during the

time the front frame of each series is being shifted to a position in the rear of the next adjacent series.

Pivots connected to the bar 22 and arranged within the space between the partitions 18 and 20 is a series of rods such as 52, there being one of these rods for each of the slots 49. Pivots mounted on the upper edge of the free end of each rod 52 is a dog or pawl 53, the free end of which is normally elevated by means of a spring 54, which latter is fixed to the rod 52, said dog or pawl normally projecting upward through the corresponding slot 49, and being adapted to engage the end of the front frame of a series to move said frame in the next adjacent series as the bar 22 is shifted lengthwise in the proper direction. Fixed to the partition 19 on the front face thereof and near the top and bottom edges thereof to the rear of each opening 17 is a series of leaf springs 55, the same being arranged so as to exert pressure on the card-carrying frames to force the same forward or toward the openings 17. Flat springs 56 are fixed to the inner sides of the molding strips 13 and 15 near the opening 17 at the left hand end of the apparatus for the purpose of imparting pressure to the frames as they are moved into position immediately behind said left hand opening so that said frames are forced rearwardly through the corresponding opening into the compartment between the partition 19 and roof sheet 11. Springs 57 are arranged on the inner side of the roof sheet to the rear of the right hand one of the openings 17 for the purpose of forcing the card-carrying frames forwardly through the opening between the right hand end of the partition 19 and the adjacent car end so that said frames will be successively moved into the compartment in front of the partition 19.

The card-carrying frames utilized in my improved apparatus are rectangular frames 58 of wood or metal, the same being grooved or constructed so as to receive the edges of advertising cards 59. The space in a car between the upper ends of the windows and the deck is usually curved in cross section, and consequently my improved apparatus and the card-carrying frames are necessarily curved to conform to the cross sectional shape of the space between the windows and deck.

The operation of my improved apparatus is as follows: The movement of the bar 22 toward the right hand under the influence of the weight 28 causes the bracket 47 to engage the finger 45 and move the valve 38 and parts carried thereby into the position seen in Fig. 8. When so positioned the piston 30 is at the right hand end of the cylinder 29, and the pawls or dogs 53 carried by the free ends of the rods 52 are positioned

at the right hand ends of the slots 49 immediately against the corresponding lower ends of the front frames of each series. Fluid pressure from the supply pipe 35 passes through the nipple 34 through that portion of the chamber 36 between the inner end of the valve 38 and the head 40, thence through port 37 into the cylinder 29, and as a result, the piston is moved to the opposite end of said cylinder, and consequently the bar 22 is moved a corresponding distance in the same direction. During this movement the dogs 53 in engagement with the front frames of each series move said front frames toward the left hand and the forward ends of said frames are guided rearwardly by the engagement of the lower edges of said frames against the rear sides of the blocks 50. During this shifting movement of the front frames the frames immediately to the rear of the shifted frames are held against longitudinal movement with the shifted frames by the transverse strips 51, against which the ends of the rear frames engage. The frames of each series are normally forced forward by the springs 55, and thus sufficient space is maintained to the rear of each series of frames for the shifted frames, which latter are transferred from their positions in the front of each series to positions in the rear of the next adjacent series. During the latter part of the shifting movement of the bar 22 the pawls 53 traverse the oblique portions 49^a of the slots, and thus said pawls are maintained in engagement with the shifted frames until the same are in position in the rear of the series to which they have just been shifted.

Just prior to the time the piston 30 reaches its limit of movement toward the left hand of the cylinder 29, the bracket 46 engages the finger 45, thereby moving the valve 38 inward, consequently cutting off the passage of fluid pressure through the port 37, and such movement brings the port 41 into coincidence with that portion of the port 37 between the chamber 36 and the interior of the cylinder 29. The air confined within the cylinder 29 behind the piston 30 will now escape through ports 37 and 41 to the interior of the valve 38, and from thence to the atmosphere through ports 42, and the weight 28 which was elevated during the movement of the bar 22 toward the left hand will now descend, thereby drawing the bar 22 toward the right hand, during which movement the pawls 53 carried by said bar engage against the lower left hand corners of the frames in the compartment to the rear of the partition 19, and said frames will be shifted a distance equal to their length toward the right hand. During the movement of the bar 22 toward the left hand the pawls 53 swing downward against the resistance offered by the springs 24 and ride along beneath the lower edges 130

of the frames to the rear of the partition 19, and during the movement of the bar 22 toward the right hand under the influence of the weight 28, the pawls 53 will 5 swing downward against the resistance offered by their springs 54 and ride beneath the lower edges of the front frames of each series until they reach the right hand ends of the slots 49, and then said pawls 53 will 10 be moved upward and engage the lower right hand corners of the front frames of each series.

It will be noted that in my improved apparatus the front frames of each series are 15 transferred to positions in the rear of the next adjacent series, with the exception of the transfer made at the left hand end of the apparatus wherein the same frame is displayed twice, for in transferring the frames 20 from the next to the last series at the left hand end of the apparatus to the last series, the front frame is shifted to a position in front of the left hand series, which procedure is necessary in order to bring about 25 a proper movement of the frames through the opening at the left hand end of the partition 19, so that the frames can be successively delivered to the compartment to the rear of said partition where they are engaged 30 by the pawls 23 and intermittently moved to the right hand end of the apparatus.

By my improved advertising construction the capacity of the apparatus is materially 35 increased over an apparatus utilizing a double row of moving frames, and furthermore, the panoramic or contiguous view effect is done away with by the arrangement of the alternate openings and panels. The apparatus 40 will necessarily attract attention by reason of the shifting frames, and a person looking at a frame moving away from one opening, will naturally look for said frame in the next adjacent opening, but by arranging 45 the frames in series, the same frame will not appear through successive openings, except as hereinbefore stated, at the left hand end of the apparatus.

My improved apparatus is comparatively 50 simple, very compact, and is easily and cheaply operated.

It is obvious that various changes in structural detail and modifications can be resorted to without departing from the spirit 55 of my invention, the scope of which is set forth in the appended claims.

I claim:

1. In an advertising apparatus of the class described, a wall provided with a 60 series of openings, a plurality of display members arranged in series behind each opening, and means for shifting the front display member of each series to a position in the rear of the next adjacent series.

65 2. In an advertising apparatus of the

class described, a wall provided with a series of openings, a plurality of display members arranged in series behind each opening, means for shifting the front display member of each series to a position in the rear of 70 the next adjacent series, and means for transferring the display members from the series at one end of the apparatus to the series at the other end.

3. In an advertising apparatus of the 75 class described, a wall provided with a series of openings, a plurality of display members arranged behind the wall with a series opposite each opening, and fluid-pressure-actuated means for shifting the front 80 display member of each series to a position in the rear of the next adjacent series.

4. In an advertising apparatus of the class described, a wall having a series of 85 openings, a plurality of display members arranged behind said wall with a series opposite each opening therein, fluid-pressure-actuated means for shifting the front display member of each series to a position in the rear of the next adjacent series, and 90 gravity-actuated means for transferring the display members from the series at one end of the apparatus to the series at the other end.

5. In an advertising apparatus of the 95 class described, a wall provided with a series of openings, a plurality of display members arranged behind the wall with a series opposite each opening therein, a member arranged for reciprocation behind the 100 wall, and means connected to said reciprocating member for engaging and shifting the front display member of each series to a position in the rear of the next adjacent series.

6. In an advertising apparatus of the class described, a wall provided with a series of openings, a plurality of display members arranged behind the wall with a series opposite each opening therein, a member arranged for reciprocation behind the 110 wall, means connected to said reciprocating member for engaging and shifting the front display member of each series to a position in the rear of the next adjacent series, and 115 means on said reciprocating member for transferring the display members from the series at one end of the apparatus to the series at the other end.

7. In an advertising apparatus, a plurality of independent unattached display members arranged in series, which series are spaced apart, and means for shifting the front display member of each series to a position in the rear of the next adjacent 120 series.

8. In an advertising apparatus, a plurality of independent unattached display members arranged in series, which series are spaced apart, means for shifting the front 130

display member of each series to a position in the rear of the next adjacent series, and means for transferring the display members from the series at one end to the series at 5 the opposite end.

9. In an advertising apparatus of the class described, a housing provided with a series of spaced panels on one side, a plurality of display members within the housing, 10 which display members are arranged in series with a series opposite each opening between an adjacent pair of panels, and means for shifting the front display member of each series to a position in the rear of the 15 next adjacent series.

10. In an advertising apparatus of the class described, a housing provided with a series of spaced panels on one side, a plurality of display members within the housing, 20 which display members are arranged in series with a series opposite each opening between an adjacent pair of panels, means for shifting the front display member of each series to a position in the rear of the 25 next adjacent series, and means for transferring the display members from the series at one end of the housing to the series at the other end.

11. In an advertising apparatus of the 30 class described, a housing having a series of openings, a plurality of display members arranged in series behind each opening, a member arranged for reciprocation adjacent to the housing, means for reciprocating 35 said member, means coöperating with said reciprocating member for engaging and shifting the front display member of each series to a position in the rear of the next adjacent series, and means on said member 40 for engaging and transferring the display members from the series at one end of the apparatus to the series at the other end.

12. In an advertising apparatus of the 45 class described, a housing having a series of openings, a plurality of display members ar-

ranged in series behind each opening, a member adapted to be reciprocated, fluid-pressure-actuated means for moving said member in one direction, gravity means for moving said member in a reverse direction, 50 means coöperating with said reciprocating member for engaging and shifting the front display member of each series to a position in the rear of the next adjacent series, and means on said reciprocating member for 55 transferring the display members from the series at one end of the apparatus to the series at the other.

13. In an apparatus of the class described, the combination with a suitable support and 60 a plurality of display members arranged for movement on said support, of means for shifting said display members, which means comprises a reciprocating member, devices thereon for engaging the display members 65 when the same are moved in one direction, a series of members connected to the reciprocating member, and devices mounted on said members for engaging and moving the display members in a direction opposite to that 70 in which said members are moved when engaged by the devices on the reciprocating member.

14. In an apparatus of the class described, the combination with a series of panels, the 75 same being spaced apart, of a plurality of display members, arranged in series behind the spaces between said panels, and means for successively engaging and shifting the front display member of each series to a 80 position in the rear of the next adjacent series.

In testimony whereof I hereunto affix my signature in the presence of two witnesses, this 7th day of April, 1913.

MARTIN P. SMITH.
